UNITED STATES PATENT OFFICE.

GREVILLE E. CLARKE, OF RACINE, WISCONSIN.

IMPROVED SKEIN AND BOX FOR AXLES.

Specification forming part of Letters Patent No. **77,585**, dated May 5, 1868.

To all whom it may concern:

Be it known that I, GREVILLE E. CLARKE, of Racine, in the county of Racine, and in the State of Wisconsin, have invented certain new and useful Improvements in Skein-Box for Axles; and do hereby declare that the following is a full, clear, and exact description thereof, reference being had to the accompanying drawings and the letters of reference marked thereon.

In the annexed drawings, A represents the axle of a vehicle, and is made of any suitable material, and substantially in the form shown in the drawings, the under side of the arm being provided with a suitable groove, in which the brace-rod E is placed.

B represents a thimble-skein made of cast metal, so as to fit over the end or arm of the axle A, and provided with a recess in its under side and a groove, x, under the collar, in which I cast box-metal C for the bearing, and then turn the whole down true. The thimble or adjustable arm B has also a tongue, h, made dovetail in shape, and the edges of the recess are also of similar shape, so that when the box-metal C is cast therein it is held firmly in its place.

D represents the box made to fit on or over the skein B, and is provided with a recess or chamber, r, to hold oil or grease for lubricating the axle or bearings. The box D is also provided with ribs g g, to increase the strength

thereof and hold the same from turning in the hub.

E represents a brace-rod extending from the outer end of the thimble-skein B, through the same, along a groove in the under side of the arm of the axle A, to the lug F, to which it is secured, as shown in the drawings.

The outer end of the brace E is provided with a head and washer, f, to prevent its slipping through the end of the skein B.

It will be seen that by tightening up the brace E, by means of the nut j said brace will hold a large part of the weight, and thereby greatly strengthen the axle.

Having thus fully described my invention, what I claim as new, and desire to secure by Letters Patent, is—

The skein B, having a recess on its under part filled with box-metal C, and provided with a groove, x, and tongue, and used in combination with the box D, as constructed, and the rod E connected through the axle, as specified, all constructed and used substantially as set forth.

In testimony that I claim the foregoing I have hereunto set my hand this 27th day of February, 1868.

GREVILLE E. CLARKE.
